UNITED STATES PATENT OFFICE

KENNETH HERBERT SAUNDERS, OF BLACKLEY, MANCHESTER, ENGLAND, ASSIGNOR TO
IMPERIAL CHEMICAL INDUSTRIES LIMITED, OF LONDON, ENGLAND

APPARATUS FOR CARRYING OUT REACTIONS CONTINUOUSLY IN THE LIQUID PHASE
UNDER INCREASED PRESSURE

Application filed May 18, 1929. Serial No. 364,153.

In my co-pending application Serial No. 315,906 I have disclosed a form of apparatus suitable for carrying out in a continuous manner reactions which occur in the liquid phase at an elevated temperature under the 5 vapour pressure of one or more of the components. This apparatus was an improvement over the apparatus involving coiled pipes usually proposed for such purposes and its technical advantage lies in the fact that by its use it is possible to dispense with a hydraulic accumulator as a means of keeping steady the working pressure, while at the same time allowing for fluctuations in the 10 volume of the liquid passing through the apparatus, hereafter referred to as the converter.

The present invention is concerned with certain advantages which reside in some 15 modifications of the form of apparatus which has been described in the above mentioned application, devised as a result of my experiments with this converter for the manufacture of p-nitroaniline from p-chloronitrobenzene and aqueous ammonia (although the converter is not by any means limited in its application to this particular reaction). When performing this operation, I have found that in time corrosion is liable to 20 be produced in those iron and steel parts of the converter which come in contact with the ammonia stream carrying the p-chloronitrobenzene and p-nitroaniline in solution. It is possible that this corrosion is caused by 25 ammonium chloride in spite of the presence of an excess of ammonia. The corrosion shows itself by pitting of the upper parts of the pressure-sustaining walls of the converter together with the upper part of the outside 30 and the inner side of the central tube. The ordinary grades of steel suitable for the construction of the pressure-sustaining walls of the converter are liable to attack by so strongly 35 corrosive a liquid as hot aqueous ammonium chloride while alloys and other metals known to resist are both costly and of unsuitable mechanical properties.

It is obvious that there would be difficulties in surmounting this corrosion hazard 40 when working with coils since inspection of

their interior is naturally impossible and even if they are periodically replaced an element of danger must always attend their use. My converter provides a remedy for this unsatisfactory state of affairs by slight alterations in the construction of the interior. In 55 my modified converter the incoming ammonia stream only is in contact with the pressure-sustaining walls and I construct those remaining parts which are still liable to corrosive attack, of stainless steel or of enamelled steel or in short of any suitable anti-corrosive material. In the accompanying illustration I have shown, more or less diagrammatically, an embodiment of my invention 60 useful in the performance of the described process. In this showing the figure is a view in vertical section with certain parts in elevation.

Referring to the structure shown in Fig. 1, element A is a vertical cylinder capable of 65 withstanding a high pressure and closed top and bottom in any suitable manner, for instance, by lens ring joints as shown. The converter is heated in any suitable manner to 200-250° C. Preheated ammonia liquor enters by the side arm B and is distributed in 70 the space D by the distributor ring C. It is there constrained by the stainless steel or other anti-corrosive mantle or sheath E to 75 flow downwards over the whole length of the pressure-sustaining walls until it arrives in the space F. From here it passes upwards in the annulus between the mantle E and the stainless steel central tube G. Low down in 80 the annulus is a cage H, containing packing material or plates I. The upflowing ammonia passes through the perforated bottom of the cage and meets in the packing a falling stream of melted p-chloronitrobenzene. The 85 latter is preheated and forced in by the tube J, eventually flowing out into the distributor plate K, from which it overflows by a series of holes on to the packing I. For each litre of .880 ammonia liquor I force in 150 to 200 90 grms. of molten p-chloronitrobenzene at 225° C. The solution in the hot ammonia stream is rapid and the reaction to form p-nitroaniline and ammonium chloride takes place in 95 the period of time necessary for a given part- 100

ticle in the ammonia stream to travel upwards from the distributor plate and overflow into the central tube G, from the bottom of which the solution is drawn off by the valve L. I commonly employ a contact time of 30 to 40 minutes for the reaction. It will thus be seen that the corrosive solution is at all times constrained in a space between walls of stainless steel or other anti corrosive material of which the pyrometer sheath O is also constructed. Moreover, it is easy at any time to dismantle the whole converter and examine the interior for signs of corrosion. The pressure in the converter is given by the gauge M which in this construction is protected from blockage by crystals or corrosion. The valve N is used only in emergency to blow down the contents of the annulus.

What I claim and desire to secure by Letters Patent is:—

- 20 1. In an apparatus for carrying out reactions continuously under pressure, an outer pressure retaining cylinder closed at both ends, a shorter mantle within said cylinder closed and supported at its upper end and leaving an annular space between said outer cylinder and said mantle, fluid distributing means within said annular space, a still shorter inner cylinder supported from its lower end and leaving an annular chamber between said mantle and said inner cylinder, packing within said annular chamber at its lower end, fluid distributing means above said packing, and fluid draw-off means at the bottom of said inner cylinder.
- 25 2. In an apparatus for carrying out reactions continuously at high pressures, an outer pressure retaining structure, closed at both ends, a loosely fitting mantle supported at the top within said outer structure, liquid distributing means at the upper end of said mantle and between said outer cylinder and said mantle, a reaction chamber within said mantle, fluid distributing means within said reaction chamber and overflow means within said reaction chamber for the reaction products of said liquid and said fluid.
- 30 3. The apparatus of claim 2 wherein the said mantle and the said overflow means are constructed of corrosion resistant material, while the outer pressure retaining structure is constructed of steel.
- 35 4. The apparatus of claim 1 in which the said mantle and the said inner cylinder are constructed of corrosion resistant material.

In testimony whereof I affix my signature.
KENNETH HERBERT SAUNDERS.
